UNITED STATES PATENT OFFICE.

WALTER H. MILLER, OF ORANGE, NEW JERSEY.

DEVICE FOR SHAVING PHONOGRAPH RECORDS OR BLANKS.

1,274,183.

Specification of Letters Patent. Patented July 30, 1918.

Application filed February 26, 1918. Serial No. 219,325.

To all whom it may concern:

Be it known that I, WALTER H. MILLER, a citizen of the United States, and a resident of Orange, in the county of Essex and State 5 of New Jersey, have invented certain new and useful Improvements in Devices for Shaving Phonograph Records or Blanks, of which the following is a description.

My invention relates to devices for shaving phonograph records or blanks, more particularly those in the form of a disk or tablet.

The principal object of my invention is to provide a simple, improved and inexpensive device of this character whereby the material of the record tablet containing the record grooves, that is, the outer portion, may be readily removed from the record tablet and a fresh smooth surface presented for recording.

Another object of my invention is the provision of a shaving device by the use of which a smooth surface for recording may be obtained on record tablets which have 25 large surface irregularities, such, for example, as those due to the warping of the tablet, without truing of the recording face of the tablet.

My invention also contemplates a device 30 for attaining the foregoing objects irrespective of the speed at which the shaving operation is carried on.

A further object of my invention is to provide a manually operable device especially adapted for home use, for attaining 35 the foregoing objects.

Other objects and features of my invention will be hereinafter more fully described and claimed.

40 In order that my invention may be more clearly understood, attention is directed to the drawing accompanying and forming a part of this specification, and in which:

Figure 1 is a plan view, partly broken 45 away, showing a shaving device construction in accordance with my invention;

Fig. 2 is a sectional view taken on line 2-2 of Fig. 1, showing the shaving device in operative position;

50 Fig. 3 is a fragmentary view showing the shaving device in end elevation and a portion of the record tablet in section, the shaving device being shown in operative position; and

55 Fig. 4 is a fragmental plan view similar to Fig. 1 of a modified form in which my

invention may be embodied, the pan being omitted.

The same reference characters are employed in the several views of the drawing 60 to designate corresponding parts.

Referring to the drawing, reference character 1 represents a circular pan provided with an upstanding peripheral flange 1' and preferably secured to a wooden base or support 2 in any suitable manner, as by means of screws 3. The pan 1 and base 2 comprise a support for a disk record tablet 4 to be shaved. The record 4 is removably secured to the support as by means of a stud or rod 5 extending through an opening provided in the center of the record support, a collar 6, preferably adjustably secured to rod 5 as by means of a set screw 6', bearing on the upper face of the record, and a nut 7 threaded on the lower end of the rod 5. The base 3 is provided with a centrally located aperture for the reception of the nut 7 which is screwed tightly against the bottom of the pan 1. Reference character 9 represents a 80 plate constituting the knife support. This plate is provided at one end with an extension 10 having an aperture adjacent its end in which a shouldered hollow bearing member or sleeve 11 is secured with the axis of 85 the sleeve preferably at right angles to the plate 9.

Reference characters 12 and 13 represent a pair of flat elongated shaving knives, which are detachably secured to the support 90 9 in spaced parallel relation, the upper edge portions of these knives preferably being respectively secured between a pair of parallel flanges 14 depending from the opposite side edges of the support and a pair of flat 95 members or bars 15, as by means of screws 16. A spring 17, preferably formed of a flat piece or strip of resilient metal, is secured at one end, as by means of screws 18, to the upper face of the support 9. The 100 other end of the spring is free and the spring is bent or shaped so that its free end will normally be located above and closely adjacent the upper end of the sleeve or member 11. Secured to and extending 105 upwardly from the support 9 is a handle 19, this handle preferably being attached to the support at a point in line with the axis of sleeve 11 and the screws 18.

The sleeve or bearing member 11 is adapted to be rotatably mounted on and closely fit the portion 5' of the rod 5 which extends

above the collar 6, as shown in Fig. 1, and when so mounted the support 9 and the parts carried thereby are adapted for movement over the face of the record tablet 4 about the 5 axis of the latter and of the support thereof consisting of the members 1 and 2. The free end of the spring 17, however, now engages the upper end of rod 5 and coacts therewith to yieldingly hold the support 9 in 10 raised or inoperative position, wherein the upper end of sleeve 11 is nearly in engagement with the free end of the spring and the lower or shaving edges of the knives 12 and 13 are above the face of the record tablet 4. 15 Thus it will be seen that spring 17 comprises means whereby the shaving device is biased to inoperative position. To shave the record tablet 4, the handle 19 is grasped by the hand and downward pressure is applied 20 thereto so as to force the support 9 downwardly against the action of the spring 17 until the shaving edges of the knives 12 and 13 engage the face of the tablet 4, as shown in Fig. 2. At the same time, the support 9 25 is turned or rotated by the handle 19 about the axis of rod 5 and members 1 and 2 in a right-hand or clockwise direction. The shaving edges of the knives 12 and 13 extend transversely of the record tablet and 30 are preferably parallel thereto, and these knives will continue to shave, remove or scrape off the upper surface layers or portions of the tablet so long as the operator continues to rotate the support 9 about the 35 rod 5 and to maintain sufficient downward pressure on the handle 19 to hold the support 9 in its lowered or operative position against the action of spring 17. The upper end of collar 6 is provided with a shoulder 40 20 which coacts with the lower end 21 of sleeve 11 to limit the downward movement of the sleeve 21 and support 9 so as to prevent the tablet from being shaved too thin. The collar 6 may be adjusted on the rod 5, 45 whereby the limit of downward movement of the sleeve 11 and support 9 with respect to the rod may be varied as desired and the pressure required to force the knives to shaving position against the action of spring 17 50 may be regulated.

The knives 12 and 13, as shown, are less in length than the radius of the tablet 4, preferably being of such length as to shave the tablet only for the maximum width of 55 the surface portion of the tablet which might be recorded upon. Therefore, the inner and outer portions 22 and 23 of the tablet will always be of the full thickness of the original tablet, and the intermediate 60 depressed shaved portion will be protected from injury. Furthermore, I have found that by having the outer end of the shaving knives (or knife, where but one is used) terminate within the outer edge of the tab- 65 let, the liability of producing chatter marks

or like irregularities on the outer edge portion of the shaved surface is practically obviated. If the shaving knife or knives extend to or beyond the outer edge of the tablet, I find that some of these marks are invariably produced in the shaving operation. 70

Each of the knives 12 and 13 is preferably in the form of a thin flat blade of such resiliency as to be flexed by engagement thereof with the surface of the tablet when 75 the support 9 is forced downwardly against the action of spring 17. Moreover, each of the flanges 14 and consequently each of the knives 12 and 13 is preferably rearwardly inclined, as clearly shown in Fig. 3. Consequently, the shaving edges of the knives 12 and 13 are dragged over the surface of the tablet in the rotary movement of support 9 during the shaving operation, and the surface portion of the tablet is shaved 80 or scraped off.

The knives 12 and 13 will, because of their flexibility, also readily give to and follow large surface irregularities of the tablet, such as those due to warping, and at the 85 same time will shave the surface of the tablet smooth. It is thus seen that the necessity of truing the surface of the tablet is done away with and consequently the amount of material which must be removed 90 in order to get a smooth fresh surface suitable for recording is greatly reduced.

An important feature of my invention resides in the use of the two shaving knives 12 and 13, instead of one, as is customary, carried by the support 9 in such relative position that in the operation of the device, the long transversely extending shaving edges of the knives will bear different angular relations to the radius of the tablet extending 100 through any given point on the surface thereof as they pass such point. I have found that by the use of two knives relatively disposed in this manner, any slight 105 chatter marks which may be produced by one of the knives will be absolutely effaced by the other knife, irrespective of the speed at which the shaving operation is carried on, and a recording surface will be obtained 110 which is smooth and free from all marks or 115 irregularities which will in any way interfere with the stylus in the recording operation. Even with the use of a single flexible 120 shaving knife such as described, a smooth recording surface will be obtained when the shaving operation is carried on at certain speeds.

When the shaving operation is finished, the device comprising the support 9, sleeve 11 and parts carried thereby is lifted off the 125 post 5, the nut 7 is unscrewed from the lower threaded end portion of post 5 and the blank 4 removed from the support comprising the pan 1 and base 2, and mounted on the record support or turn table of a recording ma- 130

chine. The flange 1' of pan 1 serves to retain material shaved from the tablet 4 in the pan. The record support may be provided with a suitable handle 25, preferably attached to the flange 1' of pan 1, which serves as a means for lifting the support and also for holding the same steady during the shaving operation.

In the modified form of my invention shown in Fig. 4, each of the knives 12 and 13 is secured to the support 9' at such an angle with respect to the line passing through the axis of sleeve 11, the screws 18 and handle 19, that in the rotation of the support 9' and parts connected therewith about the post 5 in the shaving operation, the material shaved from the tablet 4 will be moved inwardly along the faces of the knives to the inner smooth portion 22 of the tablet from which it may be easily and conveniently removed at the end of the shaving operation.

The support 9 or 9' and the parts applied to and carried thereby constitute a shaving device which may be made as an attachment adapted to be mounted on any suitable record support for carrying out the shaving operation.

It is to be understood that the specific embodiments of my invention shown and described herein are subject to various modifications and changes in the size, form and arrangement of their parts without departure from the spirit of the invention and the scope of the appended claims.

Having now described my invention, what I claim and desire to protect by Letters Patent is as follows:

1. A shaving device for phonograph records, comprising a knife support having means whereby it is adapted to be mounted on a phonograph disk record support for movement about the axis of said support.

2. A shaving device for phonograph records, comprising a knife support having means whereby it is adapted to be mounted for movement about the axis of a record support.

3. In a shaving device for phonograph records, a shaving member of such resiliency as to be flexed by engagement thereof with a record.

4. A shaving knife for phonograph records capable of being readily flexed by manually pressing the same against a phonograph record.

5. In a device of the class described, a record support, and a shaving device mounted for movement about the axis of said support, said shaving device being biased to an operative position.

6. In a device of the class described, a record support having mounted thereon a disk record to be shaved, and a shaving knife support mounted for rotary movement

about the center of said record, said knife support carrying a shaving knife having a long shaving edge extending transversely of the face of the record from adjacent the center thereof and terminating within the periphery of the record.

7. In a device of the class described, a phonograph record support, and a shaving knife support mounted for movement relative to said record support and carrying two shaving knives which extend transversely of the record support, said knives being so arranged that they will, in the shaving operation, occupy different angular positions relative to the record support as they pass any given point.

8. In a device of the class described, a phonograph disk record support having mounted thereon a disk record to be shaved, and a shaving knife support mounted for movement about the center of said record and carrying two shaving knives which extend transversely of the record, said knives being so arranged that they will, in the shaving operation, occupy different angular positions relative to the radius through any given point in the record as they pass such point.

9. An attachment for shaving phonograph records, comprising a knife support, said support having applied thereto a member whereby such support is adapted to be mounted for rotary movement, and a shaving knife carried by said support.

10. An attachment for shaving phonograph records, comprising a knife support, said support having applied thereto a member whereby such support is adapted to be mounted for rotary movement, and a plurality of shaving knives spaced apart and carried by said support.

11. An attachment for shaving phonograph records, comprising a knife support, said support having secured thereto a hollow bearing member or sleeve, and a resilient member secured at one end to said support and having its other end free and disposed over one end of the opening in said bearing member or sleeve.

12. In a device of the class described, a member mounted for rotary movement, said member carrying a knife which is so arranged that the material shaved will be fed thereby toward the axis of rotation of said member in the operation of the latter.

13. In a device of the class described, a member carrying one or more shaving knives and mounted for rotary movement about a given axis.

14. In a device of the class described, a member carrying one or more shaving knives and mounted for rotary movement about a given axis, and means for supporting said member comprising a resilient member.

15. In a device of the class described, a

- member carrying one or more shaving knives, said member being rotatable about a given axis and being yieldingly mounted for movement along said axis. 35
5. 16. In a device of the class described, a member carrying one or more shaving knives, said member being rotatable about a given axis and being mounted for movement along said axis, and means for limiting the axial 10 movement of said member in one direction.
17. In a device of the class described, a member carrying one or more shaving knives, said member being rotatable about a given axis and being mounted for movement along 15 said axis, and adjustable means for limiting the axial movement of said member in one direction.
18. In a device of the class described, a phonograph record support, and a member carrying a knife extending transversely of 20 said support, said member being mounted for rotation in one direction about the axis of said support in the shaving operation, and said knife inclining rearwardly from 25 said member with respect to said direction of rotation.
19. In a device of the class described, a phonograph record support, and a member mounted for rotation about the axis of said 30 support, said member carrying one or more knives extending transversely of said support, said knife or knives being so arranged
- that material shaved will be fed thereby toward the axis of said support in the rotation of said member. 40
20. In a device of the class described, a phonograph record support and a shaving knife support arranged for relative movement, said knife support carrying two shaving knives which extend transversely of the 45 record support and which are so arranged that they will, in the shaving operation, occupy different angular positions relative to the record support in shaving at any given point. 45
21. In a device of the class described, a phonograph disk record support having mounted thereon a disk record to be shaved, and a shaving knife support, said supports being arranged for relative movement about 50 the center of said record, said knife support carrying two shaving knives which extend transversely of the record and which are so arranged that they will, in the shaving operation, occupy different angular positions 55 relative to the radius through any given point in the record in shaving at such point.

This specification signed and witnessed this 23 day of Feb. 1918.

WALTER H. MILLER.
